UNITED STATES PATENT OFFICE.

BIRT SUTTON, OF DOVER, NEW JERSEY.

DIRECTION-INDICATOR FOR AUTOMOBILES.

1,343,529.

Specification of Letters Patent. Patented June 15, 1920.

Application filed April 25, 1917. Serial No. 164,476.

To all whom it may concern:

Be it known that I, BIRT SUTTON, a citizen of the United States, residing at Dover, in the county of Morris, State of New Jersey, have invented certain new and useful Improvements in Direction-Indicators for Automobiles; and I do hereby declare the following to be a full, clear, and exact description of the invention, such as will enable others skilled in the art to which it appertains to make and use the same.

This invention relates to signaling devices and is directed more particularly to an appliance for automobiles and other vehicles by which an appropriate signal may be given to indicate the intention of the operator of the vehicle as to whether he is going to turn, stop, etc.

An object of the present invention resides in the provision of a simple and highly efficient appliance of the above character which may be conveniently attached to automobiles generally without altering their construction.

A further object of the invention is to provide a signal device which when applied will coöperate with the usual tail light of the automobile whereby it may be utilized at night to signify the intended movements of the vehicle.

With the above and other objects of similar nature in view, the invention consists in the construction, combination and arrangement of parts, set forth in and falling within the scope of the appended claims.

In the drawing:—

Figure 1 is a side elevation of the body of a motor vehicle equipped with my invention, parts being broken away.

Fig. 2 is a rear elevation thereof illustrating the use of the device.

Fig. 3 is a detail view looking into the open side of the housing.

Fig. 4 is a bottom plan view of the housing and the related mechanism; and

Fig. 5 is a section taken on the line 5—5 of Fig. 3.

Referring now more particularly to the accompanying drawing, there is shown in conventional manner the body 10 of an automobile to which the invention is applied. Specifically the appliance consists of a box or casing 11 which includes a pair of spaced parallel frame members 12 of inverted U-shape that are inclosed by and have secured

thereto a housing plate 13. The bottom and one side of the casing are open as clearly illustrated while arranged between and at right angles to the legs of the frame members 12 is a bracket 14, said bracket being also of U-shape and held fixedly in place by bolts 23 passed therethrough and through the free ends of the members 12. Extending transversely between the legs of the bracket 14 is a bolt 15 upon which is pivotally mounted a plurality of bell-crank levers 16, said levers being spaced from the legs of the bracket and from each other by washers 17. The arms of each lever stand at an obtuse angle to each other, being spaced about 135°; and the upper or inner arms carry indicator plates 18 said plates being provided with such designations as L, R, and S which represent respectively left, right, and stop as denoting the intended movements of the vehicle with which the appliance is associated. The plates are normally housed within the casing and are so held by coil springs 19, corresponding ends of which are connected to the levers 16 and to hooks 20 carried by the bight portion of the bracket 14.

In order to limit movement of the plates 18 into and out of the casing there is provided a stop bar 21 having angularly directed ends 22 extending between the free ends of the bracket 14 and the adjacent frame member 12 and secured by means of one of the bolts 23. As seen in Fig. 5, this bar 21 stands in such relation to the pivot bolt 15 that when the inner arm of the bell-crank lever stands upright and the plate 18 is housed, the outer or lower arm is drawn against the inner edge of the bar 21 by the spring 19. But when the lever is swung on its pivot to a position where the plate 18 is exposed as seen in dotted lines, each arm moves through a path of about 90° and the inner arm rests upon the bar 21—the latter thus serving as a stop to check the movement of the bell-crank lever in either direction. For supporting the casing 11 and its related mechanism from the rear of the vehicle body, an arm 24 is provided which is fixed to one leg of the bracket and detachably secured by bolts 25 to the body as clearly shown. For the purpose of actuating the indicator plates so that they may be displayed selectively to the occupants of vehicles in the rear and advise them of the intention to

stop or to turn, either to the right or to the left, the following mechanism is utilized: Angle plates 26 are fixed to the bracket 14 adjacent its right portion and depend therefrom to pivotally mount a plurality of rollers 27 corresponding to the number of the plates 18 and each having trained therearound a cable 28 that is connected to the outer arm of the related bell-crank lever. These cables 28 are passed over the rollers 27 forwardly beneath the body of the vehicle and connected each to a lever 29 pivotally supported in a frame 30 located within convenient reach of the driver's seat. Thus by operating the desired lever 29, one of the plates 18 is caused to swing outwardly of the casing and in a position to be plainly seen by persons located to the rear of the vehicle so that the necessary precautions may be taken as will be evident.

As it is my purpose to employ the above described mechanism by night as well as by day, the arm 24 is so attached to the machine and the casing 11 so positioned adjacent the tail light universally provided for the vehicle so that when any one of the plates 18 is swung to exposed position it will lie directly in the path of the projected rays from the light. Thus by perforating the designations on the plates as indicated at 31 the light rays will be permitted to filter through the plate and outline the designations so that it may be readily discerned.

What I claim is:—

35 1. The combination with a motor vehicle and the tail light thereof, of a direction indicator including a casing, a plurality of in-

dicator plates mounted on bell crank levers pivoted in the casing and selectively movable outwardly thereof and into the path of the 40 light rays from the tail light, said plates being provided with perforated designations through which the light rays will project, a single stop fixed to the casing for engagement by the respective arms of the bell-crank 45 levers to limit movement of the latter in either direction, and actuating means connected independently with the bellcrank levers.

2. A direction indicator for motor vehicles comprising a casing open at its bottom and one side, a pivot bolt across said bottom, a series of obtuse-angled bell-crank levers pivoted at their angles on said bolt with their inner arms carrying indicators 55 and their outer arms standing below said casing, manually operable means connected with the outer arms for swinging the levers selectively to move their respective indicators out of the casing, springs drawing said 60 inner arms normally upward to house their indicators, and a stop bar fixedly carried by the casing parallel with said pivot bolt and disposed in position to be struck by the inner arm when it stands horizontal or be struck 65 by the outer arm when the inner arm stands vertical.

In testimony whereof, I affix my signature in the presence of two witnesses.

BIRT SUTTON.
